UNITED STATES PATENT OFFICE.

JOHN Y. KING, OF LANSDOWNE, PENNSYLVANIA.

AIR-FEEDING DEVICE.

1,384,838.

Specification of Letters Patent. Patented July 19, 1921.

Application filed December 5, 1919. Serial No. 342,754.

To all whom it may concern:

Be it known that I, JOHN Y. KING, a citizen of the United States, residing at Lansdowne, in the county of Delaware and State 5 of Pennsylvania, have invented new and useful Improvements in Air-Feeding Devices, of which the following is a specification.

My invention relates to a new and useful improvement in air feeding devices, and has 10 for its object to provide an exceedingly simple and effective device of this description which when applied to the door of a coal burning furnace may be adjusted so as to project a jet of highly heated air over the 15 fire bed in such manner as to intermingle and combine with the gases of combustion in the right proportion to cause said gases to burn with an intense heat and by thus producing perfect combustion prevent the escape 20 of carbon in the form of smoke or soot.

A further object of my invention is to provide for the regulation of the device so as to supply a larger quantity of heated air to the 25 gases arising from the coal bed when the furnace is first fired or new coal applied thereto.

A further object of my invention is to provide simple and effective means for bringing about the adjustments which 30 means shall be extended outside of the furnace within easy reach of the fireman.

With these ends in view, this invention consists in the details of construction and combination of elements hereinafter set 35 forth and then specifically designated by the claims.

In order that those skilled in the art to which this invention appertains, may understand how to make and use the same, I 40 will describe its construction in detail, referring by numerals to the accompanying drawing forming a part of this application, in which:

Figure 1, is a broken away section of a 45 portion of a furnace showing my improved air feeding device applied thereto the latter being partly broken away and sectioned to clearly show the construction and operating mechanism.

Fig. 2, is an inner end view of an air feeding device.

Fig. 3, is a central section of the hinged valve.

In carrying out my invention as here embodied, 55 1 represents the body of the device attached in any convenient manner to the

furnace door 2, and to the inner end of this body is hinged the valve 3, and while this valve may be hinged in any well known or convenient manner I here show it as being 60 hinged between the two lugs 4 formed with the body 1 having a pintle 5 passing through said lugs and the valve so that while the valve is permitted to freely swing it will be accurately guided to and from its seat. 65

The body 1 has a funnel shaped intake formed therewith which extends outside of the furnace door and leading from this intake is a passageway 7 formed through the body 1 which gradually contracts toward 70 the inner end thereof so as to gradually reduce the volume of air flowing therethrough thereby increasing the speed of said flow from the head of the body, the inner end of the body being squared off to form a seat for 75 the valve 3.

The valve 3 has a hub 8 formed thereon and through the valve hub passes a small hole 9 the hub being slotted crosswise as indicated at 10 so as to intersect the hole for 80 the purpose hereinafter explained.

11 represents an operating rod which passes through the hole 12 formed in the front wall of the intake 6 and this rod carries the ratchet teeth 13 by which it may be 85 locked in several different positions and also has a looped handle formed therewith for easy operation by the fireman, the loop permitting the operation of this rod by the poker stoking bar or other implement which 90 may be readily inserted in the loop so as to avoid burning the hands of the fireman.

The rod 11 passes the full length of the passageway 7 its inner ends contacting with the valve 3 so that when the rod 3 is pushed 95 inward to its greatest extent the valve will be forced entirely open so as to permit the outflow of the maximum volume of air to the furnace, but when the rod is drawn outward sufficiently the valve will close upon 100 its seat and thus cut off this maximum flow of air limiting the inflow of air to the furnace to the capacity of the small hole 9. By the adjustment of the rod at various points by the engagement of one of the teeth 13 with the walls of the hole 12 the valve may be set at any degree to permit a greater or lesser flow of air to the furnace.

When the valve is closed the air flowing into the intake and from thence to the passageway 7 will be gradually expanded by 110 the heat absorbed from the body and thus

its speed will be accelerated until finally issuing through the small hole 9 it will be projected in a jet of high velocity, and in order that this jet may more readily 5 mingle with the gases of combustion the cross slot 10 is formed across the outlet end of the hole 9 and so proportioned that the issuing of the jet into said slot will permit the air to first spread lengthwise of the slot 10 so as to give a fan shape thereto by the action of the walls of the slot upon the outflowing air, and I have found this to be more effective in producing perfect combustion.

15 When a furnace is first fed with fresh coal a relatively large amount of freed carbon arises from the coal bed in the form of smoke and to prevent or lessen this smoke a larger amount of air is required to enter 20 the furnace over the fire bed. This I accomplish by opening the valve 3 and admitting a relatively large quantity of heated air through the passageway 7, but as the smoke gradually diminishes by the increase 25 in heat of the fire the valve may be partially closed to decrease the amount of air flowing over the fire bed, and finally entirely closed so as to project the fan shaped jet of highly heated air in the burning gases.

30 While I have shown the body 1 as being curled upward at its inner end it is obvious that it may be made straight throughout its length or in any other desired shape the principle requirement being that it shall 35 project sufficiently into the furnace to become intensely heated from the fire bed.

Of course I do not wish to be limited to the exact details of construction as herein

shown as these may be varied within the limits of the appended claims without departing from the spirit of my invention.

Having thus fully described my invention, what I claim as new and useful is:—

1. In an air feeding device, a body having a passageway therethrough, a valve hinged to the inner end of said body adapted to partially close the passageway, a hub formed upon said valve, said valve and hub having a hole therethrough, said hub having a crosswise slot intersecting said hole, 45 and means for operating the valve.

2. In an air feeding device of the character described, a body adapted to be secured upon the door of a furnace and having a passageway therethrough, a valve hinged to 55 the inner end of the body, said valve having a hole therethrough and a cross slot intersecting said hole, an operating rod passing through the passageway and contacting with the valve, and means for latching said rod 60 in various adjustments.

3. In combination with a furnace and the door thereof, an air feeding device consisting of a body adapted to be secured to said door and project into the furnace, an intake 65 formed with the body and having a hole through its outer wall, an operating rod passing through said hole, teeth formed upon said operating rod for engagement with the walls of said hole, and a valve 60 hinged to the inner end of the body with which the inner end of the operating rod contacts.

In testimony whereof, I have hereunto affixed my signature.

JOHN Y. KING.
